The ornamental design for an automobile, as shown and described.

DESCRIPTION

1. Automobile

Fig. 1.1 is a front perspective view of the automobile;
Fig. 1.2 is a front view thereof;
Fig. 1.3 is a back view thereof;
Fig. 1.4 is a left view thereof where the right view is a mirror image
Fig. 1.5 is a top view thereof;
Fig. 1.6 is an enlarged view of Fig. 1.1;
Fig. 1.7 is an enlarged view of Fig. 1.5;
Fig. 1.8 is a front perspective view;
Fig. 1.9 is a top view;
Fig. 1.10 is an enlarged view of Fig. 1.8;
Fig. 1.11 is an enlarged view of Fig. 1.9.
The front, back, and left views of Fig. 1.8 have been omitted since they are the same as Figs. 1.2 to 1.4, respectively; the right view has been omitted as it is a mirror image of that shown in Fig. 1.4.
The broken lines depict portions of the automobile that form no part of the claimed design.
